(57) **CLAIM**

The ornamental design for a surgical instrument, as shown and described.

DESCRIPTION

FIG. 1 is a front perspective view of an embodiment of a surgical instrument.

FIG. 2 is a rear perspective view of the embodiment of FIG. 1.

FIG. 3 is a front view of the embodiment of FIG. 1.

FIG. 4 is a rear view of the embodiment of FIG. 1.

FIG. 5 is a right-side view of the embodiment of FIG. 1.

FIG. 6 is a left-side view of the embodiment of FIG. 1.

FIG. 7 is a top view of the embodiment of FIG. 1; and,

FIG. 8 is a bottom view of the embodiment of FIG. 1.

The dash-dash broken lines in the figures denote portions of the surgical instrument that form no part of the claimed design.

The wavy dash-dot-dash broken lines in the figures denote unclaimed boundaries of the surgical instrument.

1 Claim, 6 Drawing Sheets
